INVENTOR.

INVENTOR.

UNITED STATES PATENT OFFICE.

THOMAS C. SPELLING, OF NEW YORK, N. Y.

RECEPTACLE.

Application filed September 16, 1918. Serial No. 254,327.

To all whom it may concern:

Be it known that I, THOMAS C. SPELLING, a citizen of the United States, residing at New York city, in the county of New York and State of New York, have invented certain new and useful Improvements in Receptacles, of which the following is a specification.

This invention relates to receptacles, but being combined with its own peculiar mechanism for closing and unclosing the containers assembled, in the receptacle, and since the various parts contribute directly to convenience in practicing the art of conveying ideas in the form of written language, it might, for literal accuracy bear the designation of a combination.

Its purpose is the provision of a durable writepack so small that it can be conveniently carried in an upper outside vest pocket, adapted to contain a penholder, penpoints, separately, a pencil, a small supply of letter or note paper and a few envelopes, and a small quantity of ink, all securely protected from dust and moisture by locking means attached to the receptacle, the ink container being securely sealed to prevent leakage. All this without the presence or use of a stopper. An incidental, but very important, purpose is the provision of an acceptable substitute for the fountain pen, with several points of superiority. Further objects will be apparent from the following specification, appended claims and drawings, in which;

Figure 1 is a top view of the device showing the bottom piece turned to form a larger base. Figure 2 is a side elevation of Figure 1, with the bottom piece turned to normal position. Figure 3 is a bottom view. Figure 4 is a righthand edge view of Figure 2, minus the lining shown in Figure 2, a portion of the lug being broken away to expose the portion of the leg and foot members, in place. Figure 5 is a top view with the covering plate omitted. Figure 6 is a section on the line 6-6 in Figure 5. Figure 7 is a top view with the covering plate omitted and the body of the receptacle modified by leaving out the container for paper. Figure 8 is Figure 7 modified by leaving out the projecting lug, 37, and placing the pivot, 15 in the body of the receptacle. Figure 9 is a detail side view of the upper part of the

penholder showing the disunited edges of 55 the tube of which it consists.

Referring to the drawings more in detail, identical parts being represented by the same reference numeral, 1 is a single body of any suitable material, preferably a durable substance such as hard rubber, glass, fiber or celluloid; and in this opening through the top, are the containers, namely, 2, for ink, 3, for the pencil, 4, for a penholder, 5, for penpoints, and 6 for writing 65 paper and envelopes.

The bottom 12 and its mechanical adjunct are shown in Figure 1. A thin strip is cut away between the walls 7 and 8, (shown in Figure 3). Wall 8 is formed with the slanted portions 9 and 10, and the gap 11. At the center of the bottom of the body member, 1, thus modified, is the flat base member 12 attached to member 1 by means of the pivot 13, functioning as an axle for the base member. When the device is to be used, the base member is released from frictional engagement, centrally, in wall 8, as in Figure 3, by applying a finger end or the point of any small implement to the terminal 14, 80 lifting it and applying lateral pressure. The result of rotating it, as seen in Figure 1, is to considerably enlarge the area of the base, as a provision against upsetting.

The covering plate, 16, is pivoted around 85 the neck of, and under, the button 15. The neck extends through an opening in the covering plate and penetrates the substance of the lug 37, of the body. This lug may be attached to the body in any suitable 90 way. The lining 17, which may be glued to the covering plate, or fastened to it in any suitable way, may be formed of any pliable material, for instance, soft rubber. It is, in dimension, co-extensive with the 95 covering plate. Directly opposite the position of the button on the device, is the lug 18, to which the covering plate is fastened in the act of closing and locking the containers after use. It likewise may be 100 fastened to the body in any suitable way. In this lug is formed the perpendicular wall 19, and in the base portion of the lug the undercut 20. In the body of the receptacle, opposite the lug, is the depression, 105 21. The undercut is formed with an overhanging outer wall and has the shape of a slanted trench, turned conversely to the

slant 25 of the foot extension, 23. An extension of the covering plate forms the leg 22, upon which is formed the laterally extended foot 23. Likewise, there is formed 5 on the leg member 22 with its rear end depressed, the heel, 24. The foot member 23 is formed with the slanted upper edge 25 to fit against the conversely slanted inner and upper side of the undercut 20. The 10 foot and heel formations, so formed and fitted into the lug, 18, and depressing, 21 in coaction with the leg proper, will lock the leg in every direction, by simple manipulation. The leg has 15 two flat formations, the one, 26, horizontal at its junction with the covering plate, the other, 27, vertical, that is to say transversely to the plane of the horizontal section, 26, and it extends from its junction with the latter to the foot member 20 wherein the leg flattens horizontally again, the vertical section merging into the horizontal section at each end. The purpose of 25 the vertical flattening is to facilitate the lateral bending of the leg, in the act of locking. The foot is slanted as here shown to produce a wedging effect, to tighten the impact of the covering plate, and especially of the lining on the top, when the foot is 30 pressed into place. With the same object, the leg is formed with the slight upward curve, 28, which may be pressed down simultaneously with pressing the foot into the undercut. Simultaneously with the leg 35 coming into contact with the wall, 19, the heel, 24, drops into the depression, 21, in the act of locking. The depressed edge of the heel 24 is now against the interior wall, of the depression 21, and the covering plate 40 is, as a result of locking, drawn tightly against the top of the body member, and the lining, 17, presses, with resilient force, on the mouths of the containers; and as a result of this pressure, the impacted lining 45 closes and seals all the containers. To render more certain and perfect the sealing of the mouth of the ink container, the rim, 29, around the mouth of that container is 50 very slightly elevated and made relatively sharp. To avoid dragging the lining on the mouths of the containers, the front portion of the covering plate may be slightly lifted in the acts of closing and opening for use. 55 The depth of all containers is shown in Figure 6, that for penpoints being indicated diametrically. It will be understood that the penpoint container is of a suitable depth to accommodate ordinary steel pen points, or about one and one-fourth inches. 60 The upper part 30, of the penholder is tubular, its upper terminal 31 being rounded and pyramidal. It has a small elliptical incision 32 in the side of the upper terminal for inserting finger tips, or any small implement, to facilitate lifting the penholder 65 out of its container, to be used. The pyramidal form leaves space around the apex inside the top of the container sufficient to allow the insertion of finger nails, or the point of a knife blade, or other small implement for lifting the penholder upward. When so lifted out, the lower part 33 may be drawn out, reversed, and the end of it other than that carrying the shield, 36, pushed into the lower end of the upper and 70 tubular part 30. One of the penpoints, 34, may be then inserted in the shield for use. When a penpoint is too much worn, or the use of a different kind of point is desired, the penpoint container, 5, may be resorted 75 to. The upper part, 30 of the penholder, may be made of any suitable material, preferably of metal, and the edges of its shell are left disunited on one side in order to facilitate insertion and withdrawal of the 80 lower part, 33, and to secure better retaining frictional engagement. This lower part may be made of any suitable material, preferably of wood, except that the shield 36 which holds the penpoint will usually be of 85 metal. If, however, part 33 be of hard rubber or celluloid, or similar substance, the entire part may be of the same substance. There is nothing peculiar about the pencil. The slight encircling swell around it, 38, insures 90 frictional engagement with the interior walls of its container.

It is obvious that this form of penstock construction will admit of keeping the penpoint either in the shield or in the penpoint 95 container, when not in use. By keeping it in the container, a greater length of part 33 is permissible, and consequently, more length is secured for the entire implement.

The modifications shown in Figures 7 and 100 8 are merely the interior formation, leaving off the paper container and the encircling shell, 39. The other modified form, Figure 7, requires the formation thereon of the lug, 105 37. In other particulars, the construction 110 and operation of the two modified forms are substantially the same.

Inasmuch as the invention may be embodied in various other forms of varying sizes, with an increased number of containers and shifting and sealing facilities of the same character, I do not, by reason of the foregoing description and these drawings, preclude myself of the right to embody it 115 in other forms, and to supply it to other 120 uses, consistently with these specifications and claims.

It is observable that the receptacle of the dimensions here shown and described, or of even larger, and of course smaller, can be 125 constructed of a single body or block of material.

Having thus set forth and described the invention, I claim as follows:

1. The combination of a receptacle with 130

means for closing, sealing and locking compartments therein, the means consisting of a plate of resilient material, carrying on its under side a lining of pliable substance, the 5 plate pivoted on a lug attached to the receptacle opposite a lug also attached to the receptacle and undertrenched and shouldered for engagement being with a downward extension of the plate, the plate formed 10 with a downward extension having an upward curve near to and below the junction of plate and extension, also a laterally extended foot and inturned heel for engagement in locked relation, of the foot in a 15 trench in the base of the undertrenched and shouldered lug, the heel in a depression in the side of the receptacle, the lining being depressed and bound over the mouths of the compartments and on rims around the 20 mouths by resilient pull force resulting from reduction of curvature of the extension, in locked engagement.

2. The combination of a receptacle with means for closing, sealing and locking compartments therein, the means consisting of a plate of resilient material carrying on its under side a lining of pliant substance, the plate pivoted on the receptacle, the plate formed with a downward extension having 25 an upward curve near to and below the junction of the plate and extension, also a laterally extended foot and inturned heel for engagement of the foot in a trench in the base of a lug attached to the receptacle, the 30 heel in a depression in the side of the receptacle, the lining being depressed and bound on the mouths of the compartments and on rims around the mouths by resilient pull force resulting from reduction of the 35 curvature of the extension in locked engagement.

3. The combination of a receptacle with means for closing, sealing and locking compartments therein, the receptacle formed 40 with acute raised rims around the mouth of one of the compartments, the means consisting of a plate of resilient material carrying on its underside a lining of pliant substance, the plate pivoted on the receptacle, the plate 45 having a downward extension with an upward curve of the extension near to and below the junction of the plate and extension, also a laterally extended foot and inturned heel for engagement, in place, the foot in a 50 trench in the base of a lug attached to the receptacle, the heel in a depression in the side of the receptacle, the lining depressed and bound on the mouths and rims by 55 resilient pull force resulting from reduction of curvature of the extension in locked engagement.

4. In a combination of a receptacle and means for closing, sealing and locking compartments therein, a receptacle formed with 60 certain compartments positioned adjacently

to each other in an elliptical interior section, the interior elliptical section surrounded by a wall, and a compartment forming a complete circle around the interior section and within the wall.

5. In a combination of a receptacle and means for closing, sealing and locking compartments therein, a receptacle formed with a raised rim around the mouth of one of the compartments, the raised rim, in place, indenting with frictional engagement, a lining of pliable substance attached to the under-side of a plate member.

6. In a combination of a receptacle and means for closing, sealing and locking compartments therein, means for increasing the base area of the receptacle, the means consisting of a single plate of resilient material pivoted centrally on the bottom of the receptacle, the plate formed with a tongue at 80 one end for engagement in a gap in a narrow segment of the receptacle, the plate having rotary movement, either to the right or left, into locked relation on cam faces slanting upward to the tops of the walls 85 of the gap, the plate, in locked engagement, aligned, with the greater lateral dimension of the receptacle and in unlocked relation and use aligned at right angles across the greater lateral dimension.

7. In a combination, means for closing, sealing and locking compartments in a receptacle; the means consisting of a plate of resilient material, the plate revolvably attached to a pivot on the receptacle at the 100 side opposite a lug under-trenched and shouldered for engagement in place with a downward extension of the plate, the plate formed with a downward extension having an upward curve near to and below the junction of plate and extension, also a laterally extended foot and inturned heel for engagement, in locked relation, the foot in a trench in the base of the undertrenched and shouldered lug, the heel in a depression in the 105 adjacent side of the receptacle.

8. In a combination as described, means for closing, sealing and locking compartments in a receptacle, the means consisting of a plate of resilient material, the plate 110 revolvably attached to a pivot on the receptacle at the side opposite a lug under-trenched and shouldered for engagement, in place, with a downward extension of the plate, the plate formed with a downward 115 extension having an upward curve near to and below the junction of plate and extension, also a laterally extended foot and in-turned heel for engagement, in locked relation, the foot in a trench in the base of 120 the undertrenched and shouldered lug, the heel in a depression in the adjacent side of the receptacle, the plate depressed and bound on the top of the receptacle by resilient pull force resulting from reduction 125 130

of the curvature of the extension in locked relation.

9. In a combination as described, means for closing, sealing and locking compartments in a receptacle, the means consisting of a plate of resilient material, carrying on its under side a lining of pliable substance, the plate revolvably attached to a pivot on the receptacle at the side opposite a lug under-trenched and shouldered for engagement, in place, with a downward extension of the plate, the plate formed with a downward extension having an upward curve

near to and below the junction of plate and extension, also a laterally extended foot and 15 inturned heel, for engagement, in locked relation, the foot in a trench in the base of the under-trenched and shouldered lug, the heel in a depression in the adjacent side of the receptacle, the lining depressed and 20 bound on the mouths and rims around the mouths by resilient pull force resulting from reduction of curvature of the extension, in locked relation.

In testimony whereof I affix my signature. 25
THOMAS C. SPELLING.
